(57) **CLAIM**

The ornamental design for a trailer hitch retention fitting, as shown and described.

DESCRIPTION

FIG. 1 is a front, top and left side perspective view of a trailer hitch retention fitting showing my new design.

FIG. 2 is a left side elevational view thereof.

FIG. 3 is a right-side elevational view thereof.

FIG. 4 is a bottom plan view thereof; and,

FIG. 5 is a perspective view of the trailer hitch retention fitting with related environment.

The broken lines form no part of the claim and are shown only as relatable environment.
